UNITED STATES PATENT OFFICE.

JOEL BENJ. DALBEY, OF NEVADA, IOWA, ASSIGNOR OF ONE-HALF TO JAY A. KING, OF NEVADA, IOWA.

PLAITING-MACHINE.

1,242,425.

Specification of Letters Patent. Patented Oct. 9, 1917.

Application filed August 3, 1915. Serial No. 43,486.

To all whom it may concern:

Be it known that I, JOEL B. DALBEY, a citizen of the United States, and resident of Nevada, in the county of Story and State of Iowa, have invented a certain new and useful Plaiting-Machine, of which the following is a specification.

The object of my invention is to provide a machine of comparatively simple, durable and inexpensive construction, for plaiting cloth for dresses and the like.

A further object is to provide a machine having parts so constructed and arranged and so adjustable as to be readily and easily adapted for making plaits of various sizes, shapes and kinds.

Still a further object is to provide in a plaiting machine a device for supporting and feeding cloth to the plaiting mechanism, and adjustable means for imposing proper tension upon said device.

Still a further object is to provide such a machine having plaiting mechanism and having mechanism adapted to receive the plaited cloth and to hold it in its plaited position.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of a plaiting machine embodying my invention.

Fig. 2 shows an end elevation of the machine.

Fig. 3 shows an end elevation showing part of the plates installed for making ac-
40 cordion plaiting.

Fig. 4 shows a perspective view of one of the base plates.

Fig. 5 shows a front elevation of the mechanism for receiving and holding the plaited goods.

Fig. 6 shows a vertical, sectional view, taken on the line 6—6 of Fig. 5.

Fig. 7 shows a top or plan view of part of the device shown in Fig. 5.

Fig. 8 shows a front elevation of a part of the device shown in Fig. 5.

Fig. 9 shows an end elevation of the machine with the parts installed for making box plaiting.

Fig. 10 shows a vertical, sectional view, 55 taken on the line 10—10 of Fig. 9.

Fig. 11 shows a vertical, sectional view, taken on the line 11—11 of Fig. 10.

Fig. 12 shows a detail view of one end of 60 one of the brackets 19 and 20, and

Fig. 13 shows a vertical, sectional view through a modified form of one of the plaiting plates.

In the accompanying drawings I have used the reference numeral 10 to indicate 65 generally a table or supporting frame having the legs 11 and having the platform 12 provided with a central, longitudinal slot 13. Mounted on each end of the platform 12 is a pair of upright members 14. The members 14 of each pair are parallel with each other and equidistant from the respective ones of the other pairs of members 14. The members 14 are mounted on the platform 12 for lateral adjustment thereof by means of 70 bolts 15 extended through laterally extending slots in the platform 12, and through laterally extending slots 16 in the laterally extending flanges 17 at the lower ends of 75 the members 14. On the ends of the bolts 80 15 are wing nuts 18.

At the upper ends of the members 14 at each end of the machine are transverse brackets or bars 19 and 20. Each of the brackets 19 and 20 has at one end a downwardly opening slot 21 adapted to be extended from a screw-threaded bolt 22 extended through one of the members 14. The brackets 19 and 20 are held in position on the bolts 22, and may be tightly gripped 85 90 against the members 14 when desired, by means of wing nuts 23.

At the opposite end of each bracket 19 and 20 is a longitudinally extending slot 24 mounted on a similar bolt 22 capable of 95 being gripped against the member 14 by a similar wing nut 23. The bracket 20 is preferably somewhat wider from top to bottom than the bracket 19, and has in its central lower portion a tongue or bearing member 25 extending laterally from the bracket 20.

The brackets 19 and 20 have in the cen-

- tral parts of their upper edges notches 26 to receive a pin or shaft 27 supporting a roller 28. Extending around the pin or shaft 27 received in the notch 26 in the bracket 20 is a hook member 29 on which is formed a downwardly extending shank 30, screw-threaded at its lower end to receive a wing nut 23 similar to those already described. The shank 30 is slidably extended through the member 25 and between the member 25 and the wing nut 23 is a coil spring 31. It will be seen that by varying the position of the nut 23 on the shank 30 the tension on the spring 31 may be varied as may be desired for varying the tension on the roller 28 and determining the amount of force or weight of cloth necessary to rotate the roller 28 for feeding the cloth to the plaiting mechanism.
- 20 For making accordion plaiting, the following parts are provided in addition to those already described. I use a plate 32 having at its side edges downwardly extending flanges 33 designed to rest on the platform 12 and to cover the slot 13. In order to make a platform slightly raised above the platform 12 adapted to cover the slot 13 regardless of the relative positions of the members 14 of each pair of said members, 25 which platform will fill the entire space between the members 14 at each end of the machine, I have provided a plate 34 having at one side edge a downwardly extending flange 35 adapted to rest on the platform 12.
- 30 In the practical use of my device, the plate 32 is placed on the machine with the flanges 33 resting upon the upper surface of the platform 12 and with one flange 33 resting against one of the members 14 at 35 each end of the machine. The member 34 is then placed on the machine with the flange 35 resting on the platform 12 adjacent to the other members 14 at each end of the machine, and with the body of the member 34 resting on and overlapping the plate 32. The flanges 33 and 35 are provided near their ends with slots 36. The slots 36 near each end of the members 32 and 34, register with each other.
- 50 In making accordion plaiting the members 32 and 34 are placed in position as shown in Fig. 2. The cloth is then wound on the roller 28 with one edge hanging downwardly toward the platform 12. The 55 plaiting plate 38 is laid upon the member 32 if that member alone is used, or upon the member 34 if both the plates 32 and 34 are used, with one edge resting against one member 14 at each end of the machine. The 60 downwardly hanging edge of the cloth 37 is then laid on the plate 38 which has been placed in position and another plate 38 is laid over the flat edge of the cloth 37, as shown in Fig. 3, with one edge of the second plate 38 resting against the other two mem-

bers 14. The plate 38 is then pushed against the cloth from the side opposite the second plate 38 and dropped to position above and parallel with the first plate 38. The complete operation can be continued by alternately inserting the plates 38 from opposite sides and always keeping said plates with one edge against two of the members 14 at 70 opposite ends of the machine until as much of the cloth as is desired has been plaited, 75 or the capacity of the machine has been reached.

The plates 38 are preferably provided at one side edge with curled portions 39 adapted to rest one above the other on the alternate plates and to hold the plates spaced from each other at their edges where they do not have between them the opposite plates 38 and the folds of the cloth. The plates 38 are thus held against tilting downwardly 85 and outwardly from the center of the machine.

When it is desired to make ordinary accordion plaiting the members of the pairs of members 14 at each end of the machine 90 are placed equidistant from each other. When it is desired to make sunburst plaiting the members 14 at one end of the machine are set closer together than the members 14 at the other end of the machine. It 95 will be seen that when the members 38 are placed against the members 14 at each end of the machine, the resulting plaits instead of being the same width at both ends, will be wider at the end where the members 14 100 are set farther apart.

For holding plaited cloth in position after the plates 38 have been assembled for plaiting the cloth, the following holding device has been provided. The holding device 105 comprises a pair of upright members 40 having at their lower ends what I will call rearwardly extending horizontal flanges 41, provided with elongated slots 43^a extending away from the members 40. The members 40 have at their upper ends what I will call forwardly extending flanges 42 having similar elongated slots 43. Engaging devices are provided to coact with the upright members 40, and comprise upright members 44 110 having at their upper ends horizontal extensions 45 adapted to engage the under surfaces of the portions 42, and having at their lower ends horizontal extensions 46 adapted to rest below and engage the extensions 41. The extensions 45 and 46 are provided with elongated slots designed to be above and adjacent to the slots 43 and 43^a. The members 44 are provided with vertically elongated slots 47.

An angle bar 48 is mounted on the members 44 between said members and the members 40, as shown in Fig. 6, for vertical adjustment by means of bolts 49 and wing nuts 50.

In the practical use of the holding device just described, after a certain amount of cloth has been plaited by means of the plates 38, the member 46 is inserted through the slots 36 beneath the member 32 and through the similar slots beneath the member 34 when the member 34 is employed. The members 40 are then mounted on the members 44 by inserting bolts 51 through the slots in the members 46 and 41 and securing them by means of wing nuts 52 and by inserting bolts 53 through the slots in the members 42 and 45 and securing them by means of wing nuts 54. The wing nuts 50 are loosened and the angle bar 48 is lowered until it rests upon the upper plate 38 or upon the cloth above the upper plate 38, and is pressed downwardly whereupon the nuts 50 are tightened for holding the angle bar 48 in position where the plaited cloth is tightly held in plaited position. It may be incidentally mentioned in this connection that after the cloth has been plaited and put into the holding device, a cloth wrung from very hot water is passed over the plaited edges of the cloth for dampening it.

For plaiting box plaits and holding them, a different form of holding device is provided, which, for convenience in description, I will call the second holding device. One second holding device is provided for each end of the machine, and in each case comprises a pair of parallel upright bars 55 slidably mounted on bolts 56, on the ends of which are nuts 57. Secured to the outer surface of each bar 55 is an upright channel member 58. Mounted in one of the bars 55 is a bolt 59 having a head 60 adjacent to the other bar 55 and having on its outer end a wing nut 61. Mounted on the bolt 59 by means of an elongated slot is a bar or bracket 62 designed to stand in horizontal position and to extend inwardly longitudinally of the machine, as shown in Fig. 10.

On the upper surface of the inner end of the bar 62 is a notch 63 to receive a bolt 64 extended through an upright bar 65 which hangs downwardly adjacent to the bars 55 between the ends of the machine, as shown in said Fig. 10.

Cut in the edges of each bar 65 on each side thereof, is a plurality of notches. The parts 66 cut from the notches are bent outwardly and then upwardly to form supporting hooks or members. The parts 66 on one side of each bar 65 are staggered with relation to the notches on the other side of said bar.

In making box plaiting with the second holding device, the pair of members 55 at each end of the machine is placed between the members 14 with the members 55 slightly spaced from each other, and with the channel members 58 receiving the edges of the members 14. The bars 65 are hung

in position and the plate 38^b hung on the lower hook 66 of each bar 65. The cloth is then hung over the lower plate 38^b and the next plate 38^b is placed against the cloth and rested on the lower hook 66 on the opposite sides of the members 65, so that the lower edge of the second plate 38^b overlaps the upper edge of the first plate 38^b, as clearly illustrated in Fig. 11. The next plate 38^b is placed against the cloth from the side opposite that on which the second plate 38^b is located, and is supported on the second hook 66 from the bottom of the bar 65 on one edge thereof, as illustrated in Fig. 11, with the third plate 38^b overlapping the second plate 38^b, whereby is formed a box pait. The process may be continued until the capacity of the machine has been reached.

By then screwing the nuts 57 farther upon the bolts 56, the members 55 may be brought tightly together for holding all the plates 38 in position with the cloth gripped between them and the second holding device may be removed from the machine.

It may be noted in this connection that in removing either the first or the second device from the machine the nuts holding the roller supporting bracket to the member 14 at one corner and holding the said member 14 to the platform, may be loosened and the said member 14 at one corner may be moved away from the center of the machine, whereupon the holding means may be removed.

For making box plaits of different widths, a bar 65 may be provided having the hooks 66 arranged at different heights thereon.

In Fig. 13 I have shown a cross section of a plate 38^a, similar to the plate 38^b, except that the plate 38^a has laterally and upwardly extending hook members 67. The plates 38^a may be used for making box plaits by supporting one plate 38^a on the hooks 66 of the bars 65, extending the cloth over the upper edge of said plate 38^a, then placing a plate 38^a in position with its lower edge supported by the hooks 67 of the first plate, then extending the cloth over the lower edge of the second plate 38^a, then placing a third plate 38^a in position supported by hooks 66 with the lower edge of said third plate below the upper edge of the second plate and directly above the first plate, and then extending the cloth over the upper edge of the second plate and thence downwardly over the lower edge of the third plate and continuing the operation.

It will readily be seen that by various slight adjustments of the parts of my plaiting machine, a great variety of forms of plaits may be made, and that plaits of different sizes and various forms may be easily plaited. Attention is called to the simplicity of my machine, and the small

price for which it can be made, which makes the machine valuable for use in small repair and pressing establishments.

I have had a machine of this type in practical operation, and find that it takes from thirty minutes to an hour to completely plait a skirt.

It will be understood that changes may be made in the arrangement and construction of the parts of my improved plaiting machine, and it is my intention to cover by this application any such changes which may be included within the reasonable scope of my claims.

15 I claim as my invention:

1. In a plaiting machine, a supporting platform, a pair of parallel uprights at each end of said platform, part of said uprights being laterally adjustable, a bracket device 20 mounted at the upper ends of each pair of uprights for permitting the adjustment of said uprights, and a cloth receiving and supporting roller supported by said brackets and adapted to rotate with relation thereto.

2. In a plaiting machine, a supporting platform, a pair of parallel uprights at each end of said platform, part of said uprights being laterally adjustable, a bracket 25

device mounted at the upper ends of each pair of uprights for permitting the adjustment of said uprights, a cloth receiving and supporting roller supported by said brackets and adapted to rotate with relation thereto, and means for imposing tension 35 upon said roller.

3. In a device of the class described, a platform, a pair of parallel uprights at each end thereof, means for supporting cloth above said platform, and a plurality 40 of plates adapted to be placed one above the other with their ends received between the uprights at each end of the machine.

4. In a device of the class described, a platform, a pair of parallel uprights at 45 each end thereof, means for supporting cloth above said platform, and a plurality of plates adapted to be placed one above the other with their ends received between the uprights at each end of the machine, 50 part of said upright members being laterally adjustable upon the platform.

Des Moines, Iowa, July 20, 1915.

JOEL BENJ. DALBEY.
